UNITED STATES PATENT OFFICE.

CHARLES A. FERNALD AND GEORGE GALLEY, OF COLUMBUS, OHIO.

DRAFT-RIGGING.

SPECIFICATION forming part of Letters Patent No. 693,250, dated February 11, 1902.

Application filed April 8, 1901. Serial No. 54,574. (No model.)

To all whom it may concern:

Be it known that we, CHARLES A. FERNALD and GEORGE GALLEY, citizens of the United States, residing at Columbus, in the county 5 of Franklin and State of Ohio, have invented a certain new and useful Improvement in Draft-Rigging, of which the following is a specification.

Our invention relates to the improvement 10 of draft-rigging for railway-cars; and the objects of our invention are to provide a simple and reliable construction of this character which will relieve the draft-timbers from undesirable strain and otherwise protect said 15 timbers against breakage, to so construct our improved draft-rigging as to distribute the strain of the draw-bar, and to produce other improvements in details of construction and arrangement of parts, which will be more fully 20 pointed out hereinafter. These objects we accomplish in the manner illustrated in the accompanying drawings, in which—

Figure 1 is an under side view of our improved draft-rigging. Fig. 2 is a side elevation of the same. Fig. 3 is a detail view in perspective of one of the metallic holding blocks or brackets which we employ in the manner hereinafter described. Fig. 4 is a central vertical section of the rearward extension 25 of the draw-bar, illustrating its spring connection with the transverse holding-bar. Fig. 5 is a horizontal section through the forward portions of the longitudinal draft-timbers and the rear portion of the draw-bar 30 body, and Fig. 6 is an enlarged transverse section through the car-sill on line $y-y$ of Fig. 1.

Similar numerals refer to similar parts throughout the several views.

Of the draft-frame, 1 represents the parallel 40 longitudinal draft-timbers, each of which may consist of the united upper and lower sections 1^a and 2^a or be formed integral, if desired.

2 represents the front transverse draft-frame sill, which connects the ends of the 45 upper timbers 1^a, and 3 is the transverse car cross-sill or transom, against which the rear ends of the upper sections of the timbers 1 abut.

4 represents a draw-bar of any desirable 50 character, the stem or shank portion 4^a of which extends rearwardly between the tim-

bers 1 and beneath a transverse timber-connecting plate 5. In constructing the shank or inner end portion of the draw-bar the same is provided with a rigid rearwardly-extending 55 metallic yoke or oblong frame 4^b. Through a slotted opening 4^c of the shank portion 4^a passes, as indicated more clearly in Fig. 4 of the drawings, a transverse bar 6, the latter having its end portions extending loosely 60 through oppositely-located openings 1^c in the forward end portions of the timber sections or portions 2^a. With the outwardly-projecting end portions of the transverse bar 6 are connected the forward ends of rearwardly-extending 65 strain-rods 7, these rods extending on the outer sides of the longitudinal draft-timbers 1, passing loosely through openings in the sill or transom 3, and terminating at points a short distance from the rear side of 70 the latter. Upon the rear end portions of these strain-rods 7 are mounted bearing collars or stops 8, and between the latter and suitable frame-plates 9, which abut against the rear side of the sill 3, are arranged springs 75 10, the springs 10 preferably inclosing internal springs 11.

Opposite the yoke or oblong frame termination 4^b the inner sides or surfaces of the timbers 1 are suitably recessed to receive the 80 central vertically-channeled portion 12 and end spurs 13 of metallic blocks or brackets 14. The oppositely-located central vertical recesses 15 of these blocks 14 are adapted to receive the ends of a transverse holding-bar 16, 85 which extending through the frame or yoke extension 14^b of the draw-bar has its central portion provided with oppositely-projecting bosses 16^a, over which fit the ends of springs 17 and 18, the spring 17 bearing between said 90 bar 16 and the rear end of the yoke 4^b, and the spring 18 bearing between said bar 16 and the body of the draw-bar 4^a. These springs 17 and 18 are also surrounded by external springs 19 and 20. Upon the lower sides of 95 the timbers 1 we provide longitudinal metallic cover-plates 21, these plates thus covering the recesses of the timbers 1, into which are fit the projections 12 and 13 of the castings 14. As shown more clearly in Fig. 2 of the drawings, the forward ends of the plates 21 are provided on their sides with downwardly-pro-

jecting ears 21^a, which embrace opposite sides of the timbers 1 and through the slotted openings of which passes loosely the bar 6.

From the construction which we have herein shown and described it will be seen that the forward and backward strain of the draw-bar is distributed between the blocks 14 and the car transom or sill 3 and that the direct strain is thus removed from the draft-timbers. It will also be seen that the springs which are arranged in front and rear of the draft-bar 16 and the springs 10 and 11 upon the rods 7 will serve to cushion the draw-bar, and thus relieve the timbers or draft-frame-work from shock. In this connection it may be observed that it has been common to extend the draft-timbers throughout the length of the car and likewise side draft-rods; but from the construction which we have shown and described it will be seen that the side rods are terminated a short distance in rear of the sill or transom 3, and the latter is made to receive a desirable proportion of the strain resulting from a pull on the draw-bar. It will also be seen that the manner of connecting the draft-bar 16 with the draw-bar, consisting in providing said draft-bar with projections which receive springs on opposite

sides of the bar, is such as to admit of such lateral swinging movement of the draw-bar as may be required.

Having now fully described our invention, what we claim, and desire to secure by Letters Patent, is—

In a draft-rigging, the combination with parallel longitudinal draft-timbers 1, a draw-bar having its shank portion extending between said timbers and provided with a frame-like extension 4^b, of brackets 14 secured to the inner sides of the timbers 1, a bar 16 extending through the draw-bar extension and engaging recesses in said brackets, springs arranged on opposite sides of said bar 16 within said extension, a transverse bar 6 passing through slotted openings in said timbers 1 and in the draw-bar shank, draft-rods 7, engaging the ends of said bar 6 and passing through the transom or sill 3 and springs arranged between the ends of said rods 7 and the rear side of said transom, substantially as specified.

CHARLES A. FERNALD.
GEORGE GALLEY.
